SIMEON S. JACKSON, OF BOSTON, MASSACHUSETTS, ASSIGNOR, BY MESNE ASSIGNMENTS, TO THE STAFFORD COMPANY, OF BOSTON, MASSACHUSETTS, A CORPORATION OF MASSACHUSETTS.

FILLING-FEELER MECHANISM FOR LOOMS.

Application filed December 20, 1920. Serial No. 431,955.

To all whom it may concern:

Be it known that I, SIMEON S. JACKSON, a subject of Great Britain, residing at Boston, in the county of Suffolk, State of Massachusetts, have invented a certain new and useful Improvement in Filling-Feeler Mechanisms for Looms, of which the following is a specification, reference being had thereto to the accompanying drawings.

10 The invention has relation to the so-called filling-feeler mechanisms which are employed in looms for the purpose of detecting when the shuttle-contained supply of weft or filling has become depleted to the 15 predetermined extent, and thereupon bringing about action to forestall delivery of the last end of the said supply from the shuttle, so as to avoid production of a short pick in the cloth being woven which would render the cloth defective.

20 A filling-feeler mechanism comprises, ordinarily, a weft or filling-feeler, a so-called controller, and devices which under the governance of the filling-feeler and controller 25 are instrumental in bringing about the action aforesaid, (in some cases automatic replenishment of the weft-supply; in others, stoppage of the loom). The controller serves intermediate the filling-feeler and the said 30 devices; it is governed by the filling-feeler, and in turn controls such devices.

25 The invention is applicable to filling-feeler mechanisms of the class provided with side-slipping feeler-devices, i. e., feeler-devices 35 characterized by a laterally-movable feeler-member which is held from lateral movement at the time of each successive feeling action by engagement of the shuttle-contained supply of weft or filling therewith, 40 that is to say, through such engagement is held from movement longitudinally of the weft or filling-carrier occupying the shuttle, until the remaining portion of the said supply is too small to prevent such movement, 45 at which stage in the depletion of the supply the laterally-movable feeler-member is displaced in the direction of the length of the shuttle-contained weft or filling-carrier at the time of a feeling action, and as a result 50 of such displacement the change is called.

The general object of the invention is to provide improved means for operatively combining and connecting together a side-slipping feeler-device which moves forward-

ly and rearwardly in the feeling action, and 55 a controller for the devices through which a change is called in the action of the loom in which the said feeler-device is employed.

The invention consists in side-slipping feeler-mechanism having intermediate a 60 side-slipping feeler-member and a controller for the change-calling means, novel connecting and combining means comprising, essentially, a pull-link connected to one of 65 said elements and working idly relative to the other thereof in the forward and rearward reciprocating movements of the feeler-member so long as side-slipping is prevented, and through which the feeler-member in 70 slipping sidewise upon a substantially depleted weft or filling-carrier acts to pull the controller to call a change in the working of the loom.

The drawings show an illustrative embodiment of the invention in a form of feeler- 75 mechanism having a side-slipping feeler device and a rocking controller of well-known types.

In the drawings,—

Fig. 1 is a top view of certain parts at 80 one side of a loom, including the said embodiment, the parts being shown in their normal positions.

Fig. 2 is a view of the said parts in section on line 2, 2, Fig. 1, looking in the direction indicated by the arrows at the ends of such line.

Fig. 3 is a view in section on line 3, 3, Fig. 1, looking from the right hand side in Fig. 1, showing certain parts of the 90 change-calling mechanism, and the connection of the controller with the dog or latch of said mechanism.

Fig. 1 of the drawings shows only small portions of the breast-beam 1 and lay-beam 95 2 of a loom, 3 being the front-plate of the shuttle-box, and 4 a shuttle occupying the said shuttle-box. The said front-plate and the front-wall of the shuttle have the usual openings 3^a, 4^a, to permit entrance of the 100 contact-portion or feeler-tip 11 of the feeler device as the lay beats up, to provide for contact between said contact-portion or feeler-tip 11 and the filling-mass 6 upon the weft or filling-carrier 7 occupying the shuttle. 105

Referring to the feeler device shown in the drawings, it comprises, as heretofore in

some cases, a carrier-member 8 that is movable forwardly and rearwardly in the loom, and a feeler-member 9 that is mounted upon a pivotal stud 10 on the said carrier-member with capacity for transverse movement in a horizontal plane and has a rearwardly projecting contact-portion or feeler-tip 11, the filling-engaging portion 11^a of which is offset laterally with relation to the pivot 10 of the feeler-member 9. To this lateral offsetting is due the tendency of the feeler-member to swing around the pivot under the forwardly acting pressure of the shuttle-contents against its contact-portion in a feeling action. In this particular instance, the filling-engaging portion 11^a is located nearer the adjacent loom-side than the pivotal stud 10 and in consequence the said tendency takes effect in the direction toward 15 the tip of the filling-carrier 7.

The carrier-member 8 in this instance is in the usual form of a slide working in a guideway at 12^a upon a small stand 12 attached to the outer end of a main supporting 20 stand 13 extending outward from the breast-beam. A forwardly-extending reduced extension 8^a of the slide works in a hole through an upstanding portion 12^b of the forward part of stand 12. A cap or cover-plate 12^c, bridging the guideway and holding the slide down therein, is secured in place by screws 12^d, 12^e. Other forms of carrier-members and supporting means therefor known in the art are adapted to be 25 employed.

The spring-tension by which the carrier-member 8 is held normally in its rearward position, and by which it is returned to that position after having been pushed forward 30 in a feeling action by the pressure of the shuttle-contents against the end 11^a of the feeler-member, is applied in this instance by means of an expanding spiral spring 8^b surrounding the reduced forward extension 35 of the slide between the body of the slide and the upstanding portion 12^b of stand 12. The spring, as usual, yields to permit the forward movement of the feeler device that is caused by the pressure of the shuttle-40 contained filling-mass against the filling-engaging end or tip of the feeler-member at the time of a feeling action, and then returns the feeler device rearwardly to its normal position as the lay moves forwardly.

55 The controller of this embodiment of the invention is of a well-known preferred form, namely a rocking controller comprising a rockshaft 14 that is journaled in bearings 14^a, 14^b, with which the main supporting stand 13 is provided, and an arm 15 fixed upon the inner end of the said rockshaft and connecting with the devices through 60 which a change in the operation of the loom is called. The said rockshaft extends in a transverse direction from the outboard posi-

tion which the filling-feeler is required to occupy to the inboard position of the devices through which a change is called, with its outer end operatively related with the filling-feeler devices and its inner end operatively related by means of the arm 15 with the devies by which the change is called. The drawings show the latter devices as of customary character comprising a latch or dog 18 pivotally connected with an upstanding arm 19 of the usual controlling rockshaft 20, the said controlling rockshaft 20 in practice being connected operatively with the replenishing or stopping instrumentalities of the loom. The arm 15 has pivoted to its 70 extremity the link 16, which serves to couple said arm to the latch or dog, the said link having in its upper portion a slot 16^a receiving the stem of a screw 18^a projecting from the latch or dog. The engagement of 75 the tooth 18^b of the latch or dog by the shoulder 21^a of the vibrating weft-hammer or gooseneck 21 is controlled through the agency of the rocking controller. Normally, the controller holds the latch or dog clear of 80 the path of the shoulder 21^a. This result is secured in the present instance through the action of a spiral spring 22, surrounding the controller-rockshaft and having one end thereof engaged with the adjacent stand-bearing 14^a and the other engaged with a collar 23 fixed by means of a binding-screw 24 upon the controller-rockshaft. The said 85 spring operates torsionally with a tendency to keep the controller-rockshaft rocked into 90 a position in which its arm 15 and link 16 hold the latch or dog 18 elevated clear of the moving weft-hammer or gooseneck. The tension of the spring may be varied by adjustment of the collar around the rockshaft. 95 A second collar 28 is adjustably secured by a screw 28^x to the controller-rockshaft adjacent the stand-bearing 14^b, said collar having a lug 28^y thereon for engagement with the under side of said stand-bearing, to stop the 100 rotation of the controller-rockshaft under the influence of spring 22 at the desired point. Other arrangements of devices in connection with a controller for calling a 105 change are known in the art.

Having reference now to the means whereby according to my invention the side-slipping feeler-member and the rocking controller are operatively connected and combined with each other,—

In the illustrated embodiment of the invention, the outer end of the controller-rockshaft 14 is provided with a crank-arm 120 27 that is adjustably fixed upon the said rockshaft by means of a clamping screw 14^s 125 at a suitable angle, such arm in this instance extending obliquely upward and toward the front of the loom when in its normal position. From the said arm a bar 29 extends outwardly, parallel to the controller-rock- 130

shaft. The pull-link previously mentioned, shown at 26, is connected pivotally at its rear end with the feeler-member 9, and its forward portion occupies a hole in the outer end of the bar 29, within which hole the said forward portion may slide smoothly and easily. A nut or collar 26^b on the said forward portion is adapted to engage against the front side of the bar 29. When the carrier-member 8 occupies its normal rearward position under the influence of its actuating spring 8^b, the engagement of the said nut or collar with the said bar operates to hold the feeler-member 9 turned into its normal presentation position which is determined through the engagement of a shoulder or lug 9^b of the said feeler-member with a stop 9^c on the carrier-member. This takes place without occasioning any rocking of the controller 20 from its normal position.

During the normal working of the loom prior to substantial exhaustion of the supply of weft or filling in the shuttle, the pressure of the wound mass of weft or filling against the filling-engaging end 11^a of the feeler-tip 11 at each beat-up of the lay carries the feeler-member 9 and its carrier-member 8 forwardly in the loom, and as soon as this forward pressure is relieved the spring 8^b restores the slide and feeler-member to their normal rearward positions. In this feeling operation, the filling-engaging portion 11^a of the feeler-tip is held from slipping sidewise when it engages with a substantial amount of filling, the whole organization being pushed forward in the advance of the lay without any turning movement of the feeler-member 9 about the pivotal stud 10, and the pull-link 26 simply slips freely forward through the eye-hole in bar 29, and is drawn rearwardly through such hole by the return of the feeler-member 9 to the latter's normal rearward presentation position, without affecting the position of the bar 29 and the controller, and consequently the latch or dog 18 continues to be held out of engagement with the weft-hammer or gooseneck 21.

When, however, there is not sufficient weft or filling remaining to hold the filling-engaging tip 11^a from slipping sidewise along the nearly bare filling-carrier occupying the shuttle, the push of the said filling-carrier against the said filling-engaging tip causes such side-slipping to occur before or as the carrier-member 8 begins to move forwardly in its guideway, thereby rotating the feeler-member 9 about its pivot 10 and moving the arm 9^b and the attached pull-link 26 rearwardly. Thereupon, through the engagement of nut or collar 26^b, with bar 29, the latter is drawn rearwardly, rotating the controller against the resistance of its spring 22 and lowering the latch or dog 18 into position to be engaged by the shoulder 21^a

of the weft-hammer or gooseneck. Through such engagement the latch or dog is moved forward and the controlling rockshaft 20 is rocked so as to call a change in the working of the loom.

It will be perceived that in the organization as shown and described I provide the feature of a loosely-connected pull-link intermediate the controller and the side-slipping feeler-member, working idly in connection with the said elements in the reciprocating movement of the feeler-member so long as side-slipping is prevented, and through which the feeler-member in slipping sidewise acts to pull the controller to call the change. In the drawings the idle working of the pull-link is provided for by permitting it to slip through the hole in the bar 29 to the extent limited by the nut or collar 26^b in the movement of the feeler-member rearwardly. The loose connection and idle working to a predetermined extent may be provided for otherwise in practice.

As will be apparent from the foregoing, the connections comprising the crank 27 with its bar 29, and the pull-link 26, not only serve to enable the feeler-member to actuate the controller so as to rock the latter to call a change in the working of the loom when sidewise movement of the feeler-member takes place, but also enables the spring 22 surrounding the controller-rockshaft to hold the feeler-member and its tip normally in its regular presentation position.

I have shown and described the best form of embodiment of the features of the invention that has thus far been devised by me, but in practice the form and arrangement of parts may be varied more or less from what is shown in the drawings.

The said embodiment has been designed with the object in view of providing for slipping movement of the feeler-member in the direction toward the tip of the filling-carrier 7, as required in case the filling-carrier is conical adjoining the head thereof, as shown. The feeler-tip 11, accordingly, is located at the inner side of the pivot or fulcrum 10 for feeler-member 9, and the feeler-member arm with which pull-link 26 engages extends outward from the said pivot or fulcrum. On account of the location of the pull-link outward beyond the pivot or fulcrum 9, the crank-arm 27 is provided with the lateral extension constituted by bar 29. In embodiments in which the pull-link is employed in connection with a feeler arranged to slip in the opposite direction, namely outwardly toward the filling-carrier head, in which case the feeler-tip and pull-link will be transposed with relation to pivot or fulcrum 10, the pull-link may work in a hole in the crank-arm 27 of the controller.

What is claimed as the invention is:—

1. In a filling-feeler mechanism for looms,

- 4
- the combination with a movable controller for the change-calling means, and a side-slipping feeler-member reciprocating forwardly and rearwardly in the feeling action, 50 of a pull-link intermediate the said elements, connecting them together, working idly relative to one thereof in the reciprocating movement so long as side-slipping is prevented, and which the feeler-member in slipping sidewise actuates endwise to pull the controller to call the change.
5. In a filling-feeler mechanism for looms, 55 the combination with a rocking controller for the change-calling means having a cranked portion, and a pivotally mounted side-slipping feeler-member reciprocating forwardly and rearwardly in the feeling action, 60 of a pull-rod connected with said feeler-member and having controller-engaging means reciprocating in the normal working of the feeler-mechanism in a path lying wholly forward of said cranked portion, and 65 in case of side-slipping of the feeler-member moved rearwardly into engagement with said cranked portion to rock the controller to call the change.
6. In a filling-feeler mechanism for looms, 70 the combination with a side-slipping feeler-member reciprocating forwardly and rearwardly in the feeling action and having a lateral arm, and a movable controller for the change-calling means having a cranked 75 portion, of a pull-rod attached to said feeler-member arm having a portion adapted to engage the said cranked portion in case of side-slipping of the feeler-member and rock the controller to call the change. 80
7. In a filling-feeler mechanism for looms, the combination with a movable controller for the change-calling means, and a side-slipping feeler-member reciprocating forwardly and rearwardly in the feeling action, 85 of a loosely connected pull-link intermediate the said elements working idly in connection therewith in the reciprocating movement of the feeler-member so long as side-slipping is prevented, and through which the feeler-member in slipping sidewise acts to pull the controller to call the change. 90
- In testimony whereof I affix my signature in presence of two witnesses.
